RESILIENT HEEL

Filed June 15, 1932

FIG. 1.

FIG. 3.

FIG. 4.

FIG. 2.

Inventor

Bernard Kind

UNITED STATES PATENT OFFICE

BENJAMIN KIND, OF BALTIMORE, MARYLAND

RESILIENT HEEL

Application filed June 15, 1932. Serial No. 617,456.

This invention relates to rubber heels, and the principal object of the invention is to form the heel with an inner part of greater resiliency than the rest of the heel.

5 Another object of this invention is to so form the rubber heel as to confine within the interior thereof, when secured in position on a shoe a body of air which will render the heel extremely resilient and shock absorbing.

10 Another object of this invention is the provision of a tread portion on the heel which will present a flat tread surface of substantial area and which will further more prevent the heel from slipping.

15 A still further object of this invention is to provide a heel of this character which is low in cost, capable of being easily manufactured, and which will be easy to apply to a shoe as are the heels of conventional design.

20 Other objects of this invention will become apparent as a description thereof, given hereunder proceeds, reference being now had to the accompanying drawing, wherein:—

Fig. 1 is a view of the tread face of the heel.
25 Fig. 2 is a top view of the heel.

Fig. 3 is a sectional view taken on line 3—3, Fig. 1, with the tread downward.

30 Fig. 4 is a similar sectional view taken on line 4—4, Fig. 1, and additionally showing in dotted lines that portion of the shoe to which the heel is attached.

35 In these views 1 indicates the body of the heel, which is provided with a flexible tread portion 2 and a wall portion 3 extending around the entire periphery of the heel and being substantially of uniform depth and thickness. The heel is provided with the usual nail receiving holes 4 in the wall 3 thereof for securing the heel to the shoe in 40 the manner well known.

45 Preferably as shown in Fig. 1, the tread portion 2 of the heel is made similar in shape thereto, the tread portion being located wholly within the outer peripheral edge of the heel. The tread portion 2 of the heel is provided with a flexible and resilient flat tread surface 5 giving a large area of surface contact, with the consequent reduction of slippage to a minimum. The top of the tread portion 2 as shown in Figs. 3 and 4 merges

55 into an upstanding wall 3, offset with respect to said tread portion, the bottom end 6 of said wall lying in a plane parallel to the plane of the tread surface 5 and spaced a short distance therefrom. This distance is preferably substantially equal to the thickness of the tread portion 2. The depth of the wall 3 is such that said depth plus the thickness of the said portion 2 will not exceed the normal thickness of a conventional heel. The bottom end 60 of the wall 3 forms a shoulder which may support the outermost peripheral portions of said tread portion 2.

55 Formed centrally within the tread portion 2 is a concave depression 7, the apex or bottom of said concavity preferably lying in the same plane as the bottom end 6 of the wall 3 as clearly shown in Figs. 3 and 4. A supporting boss 8 made of the same material as the heel 1 is formed integral with the tread portion 2 and extends upwardly from the inside of the tread portion 2 and in direct alignment with the depression 7, the top of said boss 8 terminating and lying in the same plane with the top end 9 of the wall 3 65 for supporting the central portion of the tread portion 2. There is thus formed between the boss 8 and the wall 3 in the interior of the heel a somewhat annular pocket or recess 10, most clearly shown in Fig. 2. 70

75 When the heel shown in section in Fig. 4, is attached to shoe 11 shown partly in dotted lines in Fig. 4, there is entrapped within the recess 10 in the heel a body of air which to all intents and purposes will function as 80 a cushion of air. This cushion of air will be compressed by the flexible and resilient tread portion 2 supported between the boss 8 and wall 3 which upon shocks being imparted thereto will yield inwardly to a certain degree to coact with a cushion of air in absorbing said shock. Due to the large tread surface 5 provided, the cushion of air will be acted upon at any angle the tread portion may be acted upon by the shock. 85 The wall 3 terminating short of the tread portion 2 will not interfere in any degree with the action of said tread portion. It will thus be seen that there is provided a heel 90 which will function to cushion all shocks 95

to which it may be subjected and which furthermore is externally efficient and of pleasing design. Due to its large tread portion and flat tread surface there are no unsightly bulges to cause any discomfort to the wearer.

In order to provide for the heel a larger tread surface the heel 1, as described above may be modified by eliminating the recess and the shoulder created by bottom end 6 10 of wall 3 and tread surface, and substituting for it a flat tread surface extended and moulded integrally with surrounding wall of uniform depth and thickness and extending around the entire periphery of said tread portion.

I desire it to be understood that I may make such changes in the construction and in the combination and arrangement of the several parts, provided that such changes 20 fall within the scope of the submitted claims.

What I claim is:

1. A rubber heel comprising a tread portion having a flexible flat tread surface, a wall integral with said tread portion and 25 offset with respect thereto, the bottom end of said wall being spaced from said tread surface and substantially parallel thereto, a concave depression formed in said tread portion, the bottom of said depression being in 30 same plane with bottom of said wall, and a boss integral with the interior of said tread portion and positioned directly above said depression.

2. A rubber heel comprising a tread portion having a flexible flat tread surface, a wall integral with said tread portion and offset with respect thereto, the bottom end of said wall being spaced from said tread surface and substantially parallel thereto, 40 a concave depression formed in said tread portion, the bottom of said depression being in the same plane with the bottom end of said wall, and a boss integral with the interior of said tread portion and positioned directly 45 above said depression, said wall and said boss being substantially of the same height.

3. A rubber heel comprising a tread portion having a flexible flat tread surface, a wall integral with said tread portion forming a shoulder with respect to said tread portion, said shoulder lying in a plane parallel to and above said tread surface, a concave depression formed in said tread portion, the bottom of said depression lying in the same 55 plane with said shoulder, and a boss integral with the interior of said tread portion and positioned directly above said depression.

4. A rubber heel comprising a tread portion having a flexible flat tread surface, a 60 wall integral with said tread portion forming a shoulder on said wall offset with respect to said tread portion, a flexible flat tread surface provided on said tread portion, said shoulder lying in a plane parallel to 65 and above said tread surface, a concave de-

pression formed in said tread portion, the bottom of said depression lying in the same plane with said shoulder, and a boss integral with the interior of said tread portion and positioned directly above said depression, 70 the top surfaces of said wall and boss lying substantially in the same place.

5. An elastic heel of resilient material comprising a tread portion, having a flexible flat tread surface, a wall integral with 75 said tread portion and of uniform depth and thickness and extending around the entire periphery of said tread portion, a concave depression formed in said tread portion, and a boss integral with the interior of said tread portion and positioned directly above said depression, the top surfaces of said wall and boss lying substantially in the same plane, the cross sectional dimensions of the boss and that of the concave depression being substantially the same, the boss and the wall forming in the attaching surface of the heel an annular air pocket of substantial dimensions.

In testimony whereof I have hereunto affixed my name.
